PAGE 7

Fig. 10

FIG. 11

FIG. 12

FIGURE 1 is a side elevational view of a velocipede having a boat-like configuration showing my new design;

FIGURE 2 is a top plan view thereof;

FIGURE 3 is a front elevational view thereof;

FIGURE 4 is a rear elevational view thereof;

FIGURE 5 is a side elevational view wherein an outboard motor has been attached to the rear of the boat-like configuration;

FIGURE 6 is a top plan view thereof;

FIGURE 7 is a front elevational view thereof;

FIGURE 8 is a rear elevational view thereof;

FIGURE 9 is a side elevational view of FIGURE 1 wherein a windshield and bowlight have been added to the boat-like configuration;

FIGURE 10 is a top plan view thereof;

FIGURE 11 is a front elevational view thereof; and

FIGURE 12 is a rear elevational view thereof.

This application is a continuation of the following ap-

plications: Ser. No. D.2,779, filed June 22, 1966; Ser. No. D.2,780, filed June 22, 1966; and Ser. No. D.2,781, filed June 22, 1966, now abandoned.

I claim:

The ornamental design for a velocipede having a boat-like configuration, substantially as shown and described.
